UNITED STATES PATENT OFFICE.

NAPOLEON BEAUREGARD AND GEORGE J. WHEELOCK, OF SAN FRANCISCO,
CALIFORNIA.

MACHINE FOR STRAIGHTENING ROUND BARS.

SPECIFICATION forming part of Letters Patent No. 320,531, dated June 23, 1885.

Application filed August 7, 1884. (No model.)

To all whom it may concern:

Be it known that we, NAPOLEON BEAUREGARD and GEORGE J. WHEELOCK, both of San Francisco, State of California, have invented a new and Improved Round-Metal-Bar Straightener, of which the following is a specification.

The invention relates to those machines used in rolling-mills and machine-works for smoothing and straightening round-metal bars, either immediately after they pass from the forming-rollers and while they are still hot, or at any time afterward when they are cold.

The invention consists in a combination of parts by which the bars are slowly fed in a longitudinal direction between three rollers, the two lower ones being simultaneously revolved in the same direction by suitable mechanism, and the upper one revolving independently by the action of the bar passing through.

The object of the invention is to expedite the operation of straightening the bar and smoothing its surface, and to provide means for giving the bar a more perfect and mercantable finish than heretofore obtained.

In the accompanying drawings, Figure 1 is a side elevation of my machine. Fig. 2 is a view of the feeding end. Fig. 3 is a view of the end from which the machine is driven. Fig. 4 is an end view of the bracket of the feed mechanism. Fig. 5 is a sectional view of one of the boxes which supports the horizontal shaft, and Fig. 6 is a diagram illustrating the rollers when all are set askew to the axial line of the bar to accelerate the feeding of the bar through the rollers.

In all the figures like letters of reference indicate like parts.

A A A are three rollers, of, say, twelve inches diameter and five feet long, with journals which rest in the boxes B, carried in the housings C C. The boxes for the lower rollers may be stationary or adjustable as to height and spread to set the rollers at any degree of angularity (within limits both vertically and horizontally) with the axial line of the bar which passes through to be straightened—that is to say, each roller may be slanted both vertically and horizontally. The upper roller, however, must be adjustable ver-

tically to accommodate different sizes of the bars, and may be adjusted horizontally to set it obliquely with the axial line of the bar. This setting of the rollers obliquely or askew is for the purpose of accelerating the feeding of the bars through the rollers.

D D are frames fitted in the housings, in which the upper boxes are adjusted sidewise. These frames are raised and lowered simultaneously when the height of the upper roller is adjusted. The frames are each suspended from cross-bars E E by the rods F F F F, the cross-bars being suspended from the short ends of the weighted levers G, which have their fulerums at H, supported on a cross-beam of the building in which the machine is erected.

I I are strong screws, which pass through the cap of the housing and bear at their points on the top of the frames D D to prevent them rising by the action of the counter-balances beyond the point to which the screws will permit. The upper ends of these screws are fitted with bevel-gears J J. Upon these rest boxes K K, fitted in such a manner as to let the wheel revolve without moving the box. As shown in Fig. 5, the bottom of the box has a circular rim fitting a recess in the plate of the gear. Over the edge of this rim is overlapped an annular plate, which is bolted fast to the gear. In this way the box is held, but the gear is free to revolve.

The shaft L rests in the boxes K K, and is fitted with the bevel-pinions M M. These engage with the gears J J, and on the end of the shaft is the hand-wheel N to turn it by. When this hand-wheel is turned in one direction, the screws I I move down and press upon the frames D D, and bring the top roller in closer relation with the lower ones. When the hand-wheel is turned in the opposite direction, the screws rise and the counter-balances lift the upper roller away from the lower ones.

O is the feed-roller, which draws the bar forward to pass it between the main rollers. It is supported on the end of the shaft P, upon which it has a slight lateral play to accommodate any variation that may occur in the adjustment of the lower rollers; also, to provide for any sudden bends in or protuberances on

- the bar, tending to throw the roller to one side or the other. There are springs Q Q on each side to maintain the roller in its normal position when the side strain is removed.
- 5 The shaft P is carried in the bearings R R', which are cast on the bracket S. On the end of this shaft is a gear-wheel, T, which engages with the pinion U, carried on the shaft V. This shaft is driven from any source of power by 10 a rope or belt passing over the pulley V'. W is a roller resting on top of the bar. It is carried on the rounded end of the swinging lever X, which has its fulcrum at x, and is connected with the nut Y on the screw Z. This 15 screw bears at its point in the bearing R', and when revolved by the hand-wheel Z' vibrates the lever X up or down, either to press the roller W on the bar or to release the bar from such pressure, as the case may be.
- 20 The bracket S is held and supported on a single fulcrum-bolt, a, so that whatever sized iron within the capacity of the machine is passed through, the feed-roller will swing up or down to suit, and with it the holding-down 25 roller on top.
- 25 The upper roller is adjusted obliquely with relation to the lower ones by fastening a screw, b, to one side of each of the boxes carrying it, the screws having a joint at d.
- 30 On the end of the screws are miter-gears, which engage with others on the ends of a connecting-shaft, e, which has a hand-wheel, f, upon it, and is borne in the bracket-bearings g g bolted to the main frame. When the shaft 35 is turned by the hand-wheel, one box is drawn forward and the other pushed back, and thus the roller is set at any desired angle.
- 35 The lower rollers are set obliquely by putting thin shims under the boxes at one end 40 and turning back the side screws, h, which bear their points against the boxes of the other end.
- 40 The matter of setting the full set of rollers will depend upon the desired speed of the feed, the greater the speed the greater the angularity, and vice versa. If the rollers be all 45 set parallel, then the operation of the roller O must be relied upon entirely for passing the bar through.
- 50 There is provided on each of the lower 55 rollers a spur-wheel, i. (In Fig. 3 we have marked only the "pitch" lines by dots.) These engage with a spur-pinion, j, revolving on an intermediate spindle, k, projected from the housing. On this spindle is another gear-wheel, l, which engages with the pinion m on the counter-shaft n, on which the driving-pulley o is placed. p is a fly-wheel, and q are 60 bearings supporting the shaft.
- 55 The operation is as follows: For the smaller-sized bars—say below four inches diameter—
- all the rollers are set parallel, and the hand-wheel N is moved until the rollers are set the required distance apart. The bar is then entered between the rollers, and the small roller W is pressed down upon the bar by turning the hand-screw Z. The machine is then started by shipping the driving-belt in the usual manner, and the bar will be steadily progressed through the rollers to the effect of 65 smoothing and straightening its surface in a thorough manner, a little water being trickled on the bar as it enters between the rollers. If the bars be of larger size than four inches the rollers may be set obliquely with relation 70 to each other, and they will be fed through 75 without other feeding device.
- What we claim as our invention is—
1. In a bar-straightening machine, the combination of the rollers A A A, housings C C', boxes B B', frames D, and mechanism, substantially as described, for adjusting the upper roller, both horizontally and vertically, with relation to the lower ones, as and for the 80 purpose described.
2. In a bar-straightening machine, the combination of the rollers A A A, housings C C', boxes B B', frames D, and mechanism, substantially as described, for adjusting each roller to set obliquely with relation to the others to effect a 85 feeding motion to the bar passing between them, as and for the purpose described.
3. In a bar-straightening machine, in combination with the straightening-rollers, the feeding device, herein described, consisting 90 of the roller O, shaft P with its revolving mechanism, roller W, lever X, nut Y, screw Z, and bracket S, supported on fulcrum-bolt a, substantially as described.
4. A bar-straightening machine, consisting 95 of three rollers, A A A, supported in suitable frames, C C', spur-gears i i on lower rollers, simultaneously driven, frames D for boxes of upper roller, counter-balances, substantially as shown, attached to frames D D, and de-100 pressing-screws I I, with their actuating machinery, as and for the purpose described.
5. In a bar-straightening machine, as a means of adjusting the upper roller to accommodate various-sized bars, the combination, 105 with said roller, of the sliding frames D, suitably held and guided in the housings C C', and carrying the boxes for journals of the roller, counter-balances E F G H, as shown, screws I I, gears J and M, boxes K, shaft L, and hand-wheel N, arranged and operating, substantially 110 as described.
